UNITED STATES PATENT OFFICE.

JOSEPH F. BENOIT, OF SANFORD, MAINE.

TENSION DEVICE FOR WINDING-MACHINES.

1,158,432.

Specification of Letters Patent.

Patented Nov. 2, 1915.

Application filed November 13, 1914, Serial No. 872,009.

To all whom it may concern:

Be it known that I, JOSEPH F. BENOIT, a citizen of the United States, residing at Sanford, county of York, State of Maine, have 5 invented an Improvement in Tension Devices for Winding-Machines, of which the following description, in connection with the accompanying drawing, is a specification, like characters on the drawing representing 10 like parts.

This invention relates to winding machines of that type which are adapted to wind yarn directly from a skein onto a bobbin and it has for its object to provide a 15 novel device of this nature by which the yarn can be wound evenly and with uniform tension on the bobbin so as to produce a bobbin of uniform hardness and one capable of being used in the shuttle of a loom.

20 In order to give an understanding of my invention I have illustrated in the drawings a selected embodiment thereof which will now be described, after which the novel features will be pointed out in the appended 25 claims.

Figure 1 is a vertical sectional view through a winding machine embodying my invention; Fig. 2 is a front view of the combined tension and take-up.

30 I have shown at 1 the frame of a winding machine having spindles 2 to support bobbins 3 on which the yarn is wound, said spindles being provided with the usual whirls 4 by which they are rotated. The 35 yarn is laid on the bobbins by means of a yarn guide 5 of usual construction which has a vertical traversing movement. The winding machine herein shown is of that type having a cone-shaped member 6 in which 40 the lower end of the bobbin is received and which is provided with a slot 7 through which the yarn 8 passes from the thread-guide 5, a device of this construction being adapted to wind the bobbin with the so-called weft wind. The yarn to be wound is 45 taken from a skein 9 which is supported by a swift comprising the two reels 10 and 11, the reel 10 being rotatably mounted on the fixed pivot 12 carried by the framework 13, 50 and the reel 11 being rotatably mounted on a counterweighted lever 14 pivoted at 15 to the frame, the counterweighted lever operating to hold the skein under tension.

In winding yarn directly from a skein 55 onto a bobbin difficulty is experienced in se-

curing an even laying of the yarn on the bobbin and a bobbin of uniform density, for the tension on the yarn as it is drawn from the swift varies very considerably, and as a result portions of the bobbin will be wound 60 with a small tension and other portions with a greater tension, thus making a bobbin with hard and soft spots therein. As a result, it is the common practice in textile mills to first wind the yarn from a skein onto 65 spools and then to wind from the spool onto the bobbin which is to be used in the shuttle, it being considered that this double operation is necessary in order to get a bobbin of uniform density.

70 I have provided herein a combined tension and take-up device which is adapted to be applied to any winding machine, and by means of which an even tension can be given to the yarn 8 so that a bobbin of uniform 75 density will be produced suitable for use in the shuttle of a loom. By means of my invention it is possible, therefore, to eliminate entirely one winding operation, for a properly-wound shuttle bobbin can be secured directly from the skein without the necessity of first winding from the skein onto a spool and then from the spool onto a 80 bobbin.

85 My novel combined tension and take-up device comprises a roll 16 having a roughened yarn-receiving portion 17 about which the yarn 8 is passed and which is pivotally mounted on a lever 18 pivoted at 19 to a bracket 26 secured to the frame 1. This 90 roll 16 is acted upon by a friction device which tends to retard the rotary movement given to it by the yarn as it is drawn from the skein and delivered to the bobbin. The friction device is herein shown in the form 95 of a drum 20 rigid with the spool 16 and which is encircled by a friction strap 21 of leather or other suitable frictional material, the two ends of the strap being connected together as at 22 and connected to a spring 100 23 which in turn is secured to the lever 18, the spring tending to apply the necessary frictional pressure between the band 21 and the drum 20. The lever 18 is acted upon by a spring 24 which is connected at one end to 105 the lower end of the lever, as at 25, and at the other end is connected to the bracket 26, the spring tending to throw the upper end of the lever carrying the pulley 16 outwardly thereby to take up slack in the yarn. 110

The frictional surface 17 on the roll 16 may be provided for in various ways. One simple way is to cover the roll with sand paper, emery cloth or similar material having a 5 roughened surface.

In the operation of the device the yarn 8 is taken from the skein and passed once around the roll 16 and thence led to the thread-guide 5. As the winding operation 10 proceeds the spring 24 acting on the arm 18 serves to take up any slack in the yarn 8 and thus to keep the yarn taut. As the yarn is led forward the frictional engagement thereof with the roll 16 will rotate the 15 latter and the friction strap 21 acting on the drum 20 will apply to the yarn the necessary tension so as to enable it to be laid compactly. The combined action of the swinging arm 18 and the friction strap 21 serves 20 to produce an even tension on the yarn so that a solid homogeneous bobbin can be wound even though the yarn is taken directly from the skein. Provision is also made for varying the frictional pressure of the friction strap 21 on the drum 20, and for this 25 purpose I have herein shown the arm 18 as provided with a plurality of lugs 27 to anyone of which the spring 23 may be attached. The tension on the spring 23 and 30 hence the pressure of the strap against the drum depends on the point at which the spring 23 is fastened to the arm 18. I have also provided the bracket 26 with a plurality of lugs 28 to anyone of which the 35 spring 24 may be secured so as to vary the pressure of the arm 18 against the yarn. I have demonstrated from actual practice that with a device of this nature it is possible to wind a shuttle bobbin compactly so as 40 to have a uniform density.

While I have illustrated a selected embodiment of my invention I do not wish to be limited to the constructional features shown.

45 I claim:

1. In a winding machine, the combination with a swift for supporting a skein of yarn,

a bobbin, and means to lay the yarn on the bobbin, of a combined tension and take-up device between the swift and the bobbin and comprising a pivotally-mounted spring-pressed arm, a roll rotatably mounted on the arm and having a roughened frictional surface about which the yarn is passed, a frictional drum rigid with the roll, a friction strap encircling the drum, and a spring connected to the arm and the strap for yieldingly holding the strap against the drum. 50

2. In a winding machine, the combination with a swift for supporting a skein of yarn, 55 a bobbin, and means to lay the yarn on the bobbin, of a combined tension and take-up device between the swift and the bobbin and comprising a pivotally-mounted spring-pressed arm, a roll rotatably mounted on the arm and having a roughened frictional surface about which the yarn is passed, a frictional drum rigid with the roll, a friction strap encircling the drum, a spring connected to the arm and the strap for yieldingly holding the strap against the drum, 60 and means for adjusting the tension of the spring. 65

3. In a winding machine, the combination with a swift for supporting a skein of yarn, 70 a bobbin and means to lay the yarn on the bobbin, of a combined tension and take-up device adapted to act on the yarn between the swift and the bobbin and comprising a pivotally-mounted spring-pressed compensating arm, a roll rotatably mounted on the arm and having a roughened surface about which the yarn is wound, and means frictionally to resist the rotation of said roll as it is turned by the feeding movement of the 75 yarn. 80

In testimony whereof, I have signed my name to this specification in the presence of two subscribing witnesses.

JOSEPH F. BENOIT.
